HIGHWAY MARKING DEVICE

Henry C. Snead, Jr., San Francisco, Calif.

Application September 20, 1943, Serial No. 503,171

6 Claims. (Cl. 94—1.5)

1

This invention relates generally to the manufacture and use of a device for marking lanes in highways.

Heretofore lanes in highways have been outlined by lines painted on the highway dividing the same into lanes, raised curbings in the highways for the same purpose, or devices arranged in lines on the highways which devices reflect light to the driver of the vehicle thereby outlining the lane in which he is travelling.

Lines painted upon the highways are easily obliterated by dirt and grease deposited upon the highway and are effective only under certain conditions. They are generally ineffective when the entire highway surface is wet, or for some other reason reflects light, at which time the lines and the highway merge into one reflecting surface and the distinction between the two is lost. Lines present no obstacles to a motorist who does not desire to stay within the lane which they mark and are for that reason unsatisfactory.

Devices of the second character, that is curbings in the highway, are difficult and expensive to construct; they prevent one's passing over them, in the event an emergency requires the same, and they require valuable space for their construction. Furthermore, especially at night when vehicles have their headlights in operation and when highway lights are reflected from the surface, and when the highway is wet, the whole highway including the raised curbings becomes one reflecting surface and the curbings become indistinct and merge with the highway.

Devices of the third type, that is, devices of the reflector character, are subject to the disadvantage that they are inefficient when the roadway surface is wet at which time the light which they reflect is indistinguishable from the light reflected by the wet surface of the roadway.

It is an object of this invention to provide a highway marker which presents a mark which is clearly distinguishable from the surrounding surface of the highway under all roadway conditions and under all lighting conditions.

It is a further object of the invention to provide a highway marker which presents an obstacle but which may be overrun in the event of an emergency.

It is a further object of this invention to provide a highway marker which does not take advantage of reflected light but takes advantage of the shadows it creates.

It is a further object of the present invention to provide a highway marker which is highly

2

efficient regardless of the light condition and the moisture condition of the highway surface.

Further objects of the invention will appear from the following description in which the preferred embodiments have been set forth in detail in conjunction with the accompanying drawings.

Referring to the drawings:

Figure 1 is a perspective view showing my highway marker;

10 Figure 2 is a cross-section taken along line 2—2 of Figure 1.

Figure 3 is a cross-section taken along line 3—3 of Figure 1, and

15 Figure 4 is a perspective view of a modification of my highway marker.

Figure 5 is a top plan view of the modification shown in Figure 4.

Figure 6 is a cross-section of a further modification of my road marker.

20 The preferred embodiment of my road marker illustrated in the accompanying drawings consists of a plurality of longitudinal metal strips 10, 11 and 12 which are parallel to each other. As shown, these members create two longitudinal slots 13 and 14. I have arranged a plurality of members 15 in each of these slots. These members 15 are inclined as shown in Figs. 1 and 2, those in one slot being inclined in one direction and at an angle of approximately 12° with respect to the surface of the highway, and those in the other area being inclined in the opposite direction at an angle of approximately 12° of the highway.

At frequent intervals I have provided members 16 which are adapted to support longitudinal members 10, 11 and 12 and inclined members 15 above the surface of the highway.

Adjacent the lower edges of members 10 and 12 and projecting at right angles outwardly thereto I have provided members 17 which also rest upon members 16. I have further provided longitudinal members 18 which it will be noted are permanently fastened to the upper edges of the outer members 10 and 12 and the outer edge of horizontal members 17. The outside strips 10 and 12, center strip 11, inclined members 15, members 17 and members 18 form a bridge-like construction of great strength which will prevent the collapse of the device when a truck or other heavy vehicle rolls over it.

50 In order that this device may be fastened to the highway I have provided complementary holes in members 16, 17 and 18 through which bolts 21, which have previously been embedded in the highway, may protrude. Nut and washer 55 22 and 23 are adapted to cooperate with the pro-

truding bolt and fasten the marker securely to the highway. I find it advantageous to space my device from the highway by use of members 16, as otherwise water and highway dirt would collect in the recesses between members 15 and fill the same thereby rendering the device useless as will be hereafter explained. Wind and air currents caused by passing vehicles are free to circulate under and around my device and carry off refuse. Water will drain off naturally. These self cleaning and self draining qualities are advantageous.

It will be obvious that when one's position is above and to one side of this road marker, as in Figure 1, he will see longitudinal member 18 on the side of the marker nearest to him in its entirety; he will see a portion of the upper surfaces of each of members 15 in the longitudinal slot 13 farthest from him, and he will see inclined members 15 in the longitudinal slot 14 nearest him in the following order: (a) referring to those closest to him, he will see a portion of the upper surfaces, (b) referring to those at some distance from him and continuing to the vanishing point, he will see either the very thin leading edges 24 of members 15 which reflect substantially no light and the recesses between members 15, or the lower sides of members 15 which reflect no light and the recesses between members 15. The lower side of member 15 will be indistinguishable from the rest of the recess as will be pointed out hereinafter, and will blend with the shadows created within said recess. Very little, if any, light will be reflected by the surface of the highway directly below my device. Therefore, very little if any, light from this source will be visible through the recesses between members 15 and the shadow within said recesses will not be destroyed.

Members 18 will form a continuous strip. Inclined members 15 in slot 13 farthest from the observer, will tend to form a continuous strip in that the observer sees the upper surfaces of the successive members with no breaks between. At a light distance from him, the observer will see neither the upper nor lower surface of inclined members 15 in the longitudinal slot 14 closest to him, but will look into the recesses between these members and will see, not their reflective upper surfaces, but only the shadows created within the recesses.

In the preferred embodiment of my device I have painted the members 18 one color and a portion of the upper surfaces of inclined member 15 the same color. I have painted the surfaces of members 10, 11 and 12 and the lower surfaces of members 15 a contrasting color. I also paint a portion of the upper surfaces of members 15 the contrasting color, as shown. I have found that by painting strips 18 and a portion of the upper surfaces of members 15 white, and by painting vertical members 10, 11 and 12 and the lower surfaces of members 15 black, that good results have been achieved because these colors contrast sharply and are not liable to confuse persons subject to color blindness. By having members 10, 11 and 12 and the lower portion of members 15 and that portion of each member 15 below the following member 15, all of the same color, these portions blend together and enhance the shadow effect. I create a series of relatively long and narrow recesses from which no light is reflected and by virtue of their being

adjacent each other these shadow producing recesses form a continuous line.

It is obvious that if water or other refuse collected within these recesses, their effect would be reduced or lost.

Operation of my device as a highway marker may be briefly described as follows: The driver of an automobile will see a continuous white surface 18 and a substantially continuous white surface separated therefrom, which is created by the upper surfaces of inclined members 15 in the longitudinal slot farthest from him. Because of their location, these surfaces will tend to reflect light to the observer and will be clearly visible to him. Between members 18 and the aforementioned members 15, and at some distance from him, the observer will not see the surfaces of the inclined members 15 in the longitudinal space nearest him, but will look between these inclined surfaces and will see, not reflected light, but shadows created by these members and will therefore see a black line which is thrown into relief by the two white lines bounding it. It is of course obvious that at a substantial distance from the observer the highway marker will tend to merge with the highway on the horizon and its definite characteristics will not be observed. However at that distance the necessity of a clear line of demarcation between the lanes is not great. It will be equally true that close to the observer there will be a substantial number of inclined members 15 in the slot closest to him, the upper surfaces of which will be visible to him and which will not present a black line. However in the section intermediate these two extremes, there will be definitely created a space of shadows from which no light including that from the observer's vehicle will be reflected.

In one project in which the preferred embodiment of my invention has been employed, the object was to provide a center dividing line in a six lane highway which was subject to a great deal of rain. Aside from the lights of oncoming vehicles, the driver was further subjected to the glare from permanent lights on each side of the highway at a height of 25 feet from the highway and spaced 150 feet apart. When the surface of the highway was wet, the entire surface reflected light and all prior markings were obliterated.

Members 10, 11 and 12 were 2 inches high and were spaced 3 inches apart. Members 18 were 3 inches wide. The overall width of my device was 10½ inches. Members 15 were 3 inches wide and 12 inches long. On the upper surfaces of members 15 the upper 5 inches were painted white and the lower 7 inches painted black. The overall height of my device was 3 inches.

The driver of an automobile in the lane next to my highway marker saw two continuous white strips created by member 18 nearest him and by the upper surfaces of members 15 in the longitudinal slot farthest from him. Beginning at a point approximately 15 feet in front of his automobile the driver saw the leading edges 24 of inclined members 15 in the longitudinal slot nearest him and looked into the recesses between said inclined members 15 and saw the shadows created within the recess. These shadows created a continuous black line which continued from a point 15 feet in front of his vehicle to the vanishing point on the highway some 400 to 500 feet in front of the vehicle. No light from the observer's vehicle was reflected from any of the surfaces within the recesses nearest to him, no

light from the permanently installed lights overhead was reflected and no light from oncoming vehicles was reflected. Even under conditions under which the entire highway surface would ordinarily reflect light, this black line was outstanding.

It will be appreciated that my invention is not limited to the particular device shown by the preferred embodiment, but that mechanical expediency may dictate its alterations at various times.

As shown in Fig. 6, I have provided a device in which a series of short lengths of pipe 30 are embedded in the highway surface, or in a suitable curbing, at some distance from each other. The interior of these short lengths of pipe would reflect no light and would create a series of black dots upon the highway. Suitable drainage and cleaning media may be employed to overcome drainage and cleaning difficulties should they arise. This type of device might be built into a bridge and the pipes 30 might extend through the entire structure and drain into the space under the bridge.

As shown in Figs. 4 and 5 I have provided in the middle of the highway a marker which is composed generally of a raised concrete curbing 40 having sloping sides 41 and 42. Upper surface 43 is flat and adapted to reflect light and may be painted any suitable color. In sloping surfaces 41 and 42 I have provided recesses 44. It will be appreciated that recesses 44 are separated from each other by a cement wall 45 which, is set at an angle of approximately 12° to the longitudinal axis of my device. Whereas the members 15 are set at an angle of 12° with respect to the plane of the highway, members 45 are set at an angle of 12° with respect to the plane of surfaces 41 and 42 respectively. However it will be appreciated that the members 45 have the same purpose as members 15 in the preferred embodiment in that they create shadow-creating recesses, from which no light will be reflected. In the event driving conditions are difficult, as for example when rain makes the highway surface mirror-like, the highway surface and surface 43 will reflect light but the recesses 44 in members 41 and 42 respectively will not reflect light. If one is driving at ordinary conditions, a black line between the reflective surfaces 43 and the highway surface will stand out impressively.

I also contemplate that my device may be altered by the omission of one of said longitudinal slots 13 or 14 and its complementary members 15, when an occasion arises in which it is necessary that a marker be made which need be visible from one direction only.

I also contemplate that my device is not to be restricted to use on highways but may be used wherever clear lines of demarkation are required on lighted surfaces such as airport runways, etc.

It is obvious that there are many ways in which my road marker may be made without departing from the spirit of my invention.

I claim:

1. On a highway surface a highway marker comprising a pair of spaced parallel wall portions extending longitudinally above the highway surface and vertical with respect to the same, a plurality of parallel wall portions disposed transversely between the first named wall portions and inclined at an acute angle to the surface of the highway thereby forming a series of recesses hav-

ing the open ends of the same disposed one behind the other and faced in the general direction of the highway surface along its longitudinal axis.

- 5 2. In a highway marker as defined in claim 1 in which the upper surfaces of the inclined wall portions have a light reflecting surfacing to form an area of high visibility when viewed in a direction opposite to that in which the open ends of the recesses are faced.
- 10 3. In a highway marker as defined in claim 1 in which the upper surfaces of the inclined wall portions are provided with a surfacing to reflect light to thereby form an area of high visibility when viewed in a general direction opposite to that in which the open ends of the recesses are faced and in which the inner walls of the recesses are provided with a light absorbing surface to enhance the blackness of the shadow.
- 15 4. In a highway marker as defined in claim 1 in which the recesses have a length in a direction longitudinally of the highway which is relatively great compared to the height of the same.
- 20 5. On a highway surface a marker comprising a plurality of walls serving to form a plurality of recesses disposed one behind the other, each of said recesses having an open end faced in one general direction along the longitudinal axis of the highway surface, said walls including longitudinal wall portions vertical to the highway surface, and parallel wall portions extending between the first named wall portions and inclined at an acute angle to said highway surface, the recesses serving to intercept light whereby when viewed from said general direction they appear as a series of shadows one behind the other.
- 25 6. On a highway surface a marker comprising three vertical spaced parallel members forming two adjacent parallel slots, a plurality of inclined members placed in each slot, members in one of said slots forming a series of open ended recesses placed in one direction along the longitudinal axis of the highway surface, members in the other of said slots forming a series of open ended recesses faced in the opposite direction along the longitudinal axis of the highway surface, whereby the open ends of said first series of recesses appear as a series of shadows when viewed from said first direction and the open ends of said second series of recesses appear as a series of shadows when viewed from said opposite direction.
